UNITED STATES PATENT OFFICE.

JOSEPH B. MORRILL, OF ST. LOUIS, MISSOURI, ASSIGNOR TO WESTERN ELECTRIC COMPANY, INCORPORATED, OF NEW YORK, N. Y., A CORPORATION OF NEW YORK.

TELEPHONE SYSTEM.

Application filed December 11, 1920. Serial No. 429,893.

To all whom it may concern:

Be it known that I, JOSEPH B. MORRILL, a citizen of the United States, residing at St. Louis, in the county of St. Louis, State 5 of Missouri, have invented certain new and useful Improvements in Telephone Systems, of which the following is a full, clear, concise, and exact description.

This invention relates to telephone systems having a plurality of substation circuits simultaneously bridged across the line, such for example, as are used in train dispatching. It relates more particularly to a system of this character employing loaded 15 lines.

It is well known that when loading coils are introduced into a telephone line for increasing its transmission efficiency, the electrical length of the line is very much increased. It has been found that in a line 20 having high impedance substations bridged across it and loading coils inserted, the characteristic impedance of the line is increased and standing waves are set up in the line 25 which have a harmful effect on both the volume and quality of the transmission, differing in kind and amount at the different way stations.

It is an object of the invention to eliminate the standing waves above referred to. To accomplish this, the line is terminated 30 in an impedance equal to the characteristic impedance of the line. When so terminated, the line behaves substantially as a line of 35 infinite length, and hence there are no standing waves in it.

In a system used for train dispatching the terminal way station, i. e., the one farthest from the dispatcher's substation, can be 40 given an impedance equal to the impedance of the line, but preferably this last way station is shunted by an impedance equal to the impedance of the line.

The invention further resides in an improved form of substation circuit for use 45 in connection with loaded cables.

The invention further resides in the combination with a loaded line of a plurality of substations bridged thereacross at frequent intervals.

The invention will be more fully understood from the following detailed description and claims taken in connection with the accompanying drawing, in which Fig. 1 represents diagrammatically a system employ-

ing the invention; Fig. 2 represents the preferred method of terminating the line with the desired impedance; and Figs. 3 and 4 are diagrams representing transmission conditions when the line is not properly terminated and when properly terminated, respectively.

Referring to the drawings by reference characters, a series of waystation circuits $S_1, S_2, S_3, \dots, S_{n-1}$ and S_n are connected across the line at frequent intervals. The dispatcher's substation circuit DS, shown at the left, is substantially identical with the circuit disclosed in the application of G. D. Edwards, Serial No. 315,753, filed August 6, 1919, and need not be described in detail herein.

The line, which may be a cable line, is provided at regular intervals with loading coils 10. The way stations, with the exception of the last one, S_n , are identical, and a description of the substation S_1 will suffice as a description of the others. A transformer 15 comprising line windings 16 and 17 and local windings 18 and 19, and having a core common to said windings not shown, is employed to connect the receiver 20 and transmitter 21 to the line. A switch 25 is provided, which in the position shown open-circuits the transmitter, connects the receiver in series with the windings 18 and 19 and a condenser 28, and connects the windings 16 and 17 in series with a condenser 30. When the switch is thrown to its opposite position, the transmitter with battery 31 and the receiver are connected in parallel across winding 18, windings 17 and 19 are cut out of the circuit, and winding 16 is connected across the line through a condenser 32.

The substation circuit is similar in general to that disclosed in the application of G. D. Edwards, Serial No. 289,667, filed April 12, 1919, but is an improvement thereon in that the condenser 28 is connected in series with the receiver when the circuit is in normal receiving condition, and separate condensers 30 and 32 are connected in series with the line winding in the receiving and talking conditions respectively.

It has been found by careful analysis, that a substation circuit having the constant given below will give the most satisfactory results with medium loaded

cables having up to thirty substations and with the preceding waystation circuits. Since, in this case, the impedance of substation S_n corresponds to that of substation S_1 , as described above, this impedance is very high in comparison with that of the terminating impedance 40, which is a resistance of the order of 1200 ohms. Since each of the substations is shunted by the characteristic impedance of the line, which is equal to that of the element 40, the use of the latter in shunt to the final station S_n produces very little loss in S_n . In fact, by reference to Figs. 3 and 4, it will be seen that there is not only a marked improvement in quality, but also on the average of the twenty-five stations, there is a slight improvement in the quantity of transmission by the use of a proper termination. The characteristic impedance of a long line may be obtained by the following formula, which is derived in Kennelly, "Application of Hyperbolic Functions to Electrical Engineering Problems," page 75. 70

10 loaded lines employ inductances of the order of .175 henries at a spacing of 1.66 miles. A substation best adapted for lines of No. 13 to No. 16 gauge wire, but working efficiently in the range above noted, 10 employs a transmitter having an impedance of from 15 to 20 ohms, a receiver having an impedance of about 250 ohms at 800 cycles, a transformer having a core of laminated silicon steel, and windings 16, 15 17, 18 and 19 having respectively 2900 turns of No. 32 gauge wire, 7600 turns of No. 36 gauge wire, 270 turns of No. 23 gauge wire, and 500 turns of No. 26 gauge wire, and direct current resistances respectively of 120, 1175, 1, and 5 ohms, and condensers 28, 30 and 32 having the values respectively of .67, .009 and .25 microfarads. These values are given by way of example only, it being understood that the desired 20 substation impedance can be obtained in a variety of ways. Best results are obtained when the substation in its receiving condition has an impedance of approximately 35,000 ohms with an impedance 30 angle of -20° at 800 cycles and an impedance of approximately 20,000 ohms with an impedance angle of $+45^\circ$ at 1500 cycles. This corresponds to the impedance 30 of the substation given as an example 35 above.

If the line were terminated in a final substation S_n having an impedance identical with the other substations, standing waves would be set up in the line as indicated in Fig. 3. The curves in this diagram were obtained by computations for each of the 25 equally spaced substations in a medium loaded line of No. 13 gauge wire 100 miles long. It will be noted from Fig. 3 that at the 24th substation, there is a loss of 26 miles of standard cable at 800 cycles, while at 1500 cycles the loss is only about 9 miles. This, if not corrected, would, of course, cause 50 considerable distortion of the speech signals at this substation. The curves of Fig. 4 were obtained from the same line after an impedance equal to the characteristic impedance of the line had been connected 55 across the line terminals. These results have been confirmed experimentally. One way of providing the terminal impedance is shown in Fig. 1, in which the windings 16' and 17' have been modified so that the 60 substation has the impedance to properly terminate the line. It has been found preferable, however, to employ a separate impedance as shown at 40 in Fig. 2 in shunt to the final waystation, in which case 65 the circuit of substations S_n is identical

in which Z_o is the characteristic impedance, and r , l , g and c are respectively the resistance, inductance, conductive leakage, 90 and capacity per unit length of line and ω is the frequency multiplied by 2π . For most loaded cables the impedance angle is sufficiently small that resistance 40 may be pure resistance. Since, in loaded cables, the distributed conductive leakage is negligible, the conductance of the substations, if nearly 95 equally spaced, may be regarded as uniformly distributed and this is also true of the inductance of the loading coils. 100

What is claimed is:

1. The combination with a line having series impedances and substations connected in shunt at frequent intervals, the individual impedances of such substations 110 being high relative to that of said line, of a terminal device having an impedance equal to the characteristic impedance of the line.
2. The combination with a line having a 115 plurality of substations in bridge thereof, the electrical length of said line being such that standing waves tend to interfere with transmission, of means to prevent the formation of standing waves.
3. The combination with a line having a 120 plurality of substations in bridge thereof, the electrical length of said line being such that standing waves tend to interfere with transmission, of a terminating impedance 125 the value of which is so related to the characteristic impedance of the line as to prevent the formation of standing waves.
4. The combination with a line having a 126 plurality of substations in bridge thereof,

the electrical length of said line being such that standing waves tend to interfere with transmission, of a terminating impedance to prevent the formation of standing waves, said impedance being equal to the characteristic impedance of said line.

5. In combination, a telephone line and a plurality of substations in bridge thereof, one of said substations comprising a receiver, a transformer adapted to connect said receiver across a line, and a condensive reactance associated with said transformer, said elements being so designed as to give said substation an impedance of about 35,000 ohms with an impedance angle of about -20° at a frequency of 800 cycles.

6. In combination, a telephone line and a plurality of substations in bridge thereof, one of said substations comprising a receiver, a transformer adapted to connect said receiver across a line, and a condensive reactance associated with said transformer, said elements being so designed as to give said substation an impedance of about 35,000 ohms with an impedance angle of about -20° at a frequency of 800 cycles and an

impedance of about 20,000 ohms with an impedance angle of $+45^\circ$ at a frequency of 1500 cycles.

7. A telephone substation comprising a transformer having a plurality of line windings, a plurality of condensers differing in capacity, and switching means for connecting one of said windings in series with one of said condensers across a line and for connecting a plurality of said windings in series with another of said condensers across the line.

8. The combination with a telephone line and a substation bridged across said line intermediate the ends thereof, the electrical length of said line and the position of said substation being such that standing waves tend to distort complex waves at said substation, of a terminating impedance to prevent the formation of standing waves, said impedance being equal to the characteristic impedance of said line.

In witness whereof, I hereunto subscribe my name this 29th day of November A. D., 1920.

JOSEPH B. MORRILL.
